CLAIM

The ornamental design for an electric scooter, as shown and described.

DESCRIPTION

1.-2. Electric scooter

1.1: Front

1.2: Back

1.3: Left

1.4: Right

1.5: Top

1.6: Bottom

1.7: Perspective

2.1: Front

2.2: Back

2.3: Left

2.4: Right

2.5: Top

2.6: Bottom

2.7: Perspective

The portions of the scooter shown by broken lines in design 1 form no part of the claimed design.

1 Claim, 14 Drawing Sheets
